UNITED STATES PATENT OFFICE.

EDWARD LIONEL JOSEPH, OF WESTMINSTER, LONDON, ENGLAND.

OZONE-GENERATOR.

1,368,560.

Specification of Letters Patent. Patented Feb. 15, 1921.

Application filed July 19, 1920. Serial No. 397,366.

To all whom it may concern:

Be it known that I, EDWARD LIONEL JOSEPH, of 96 Victoria street, in the city of Westminster and county of London, England, have invented certain new and useful Improvements in Ozone-Generators, of which the following is a specification.

This invention relates to ozone generators of the general type wherein each electrode 10 consists of a metallic sheet (in the form of wire gauze, for example), and the electrodes of a pair having opposite polarities extend in parallel planes and are separated by a sheet of dielectric material (mica for 15 example), while the stream of air, oxygen, or other gaseous mixture (all of which will hereinafter be referred to as "air"), which is to be ozonized, is caused to pass over the electrodes, whereof a series of pairs may be 20 employed to act upon the stream either simultaneously or in succession. In one known arrangement of such a series of pairs of electrodes the electrodes of opposite polarities alternate with one another in parallel planes throughout the series a dielectric sheet being interposed between each two adjacent electrodes, and the entire assemblage of electrodes and sheets of dielectric is 25 clamped together, the arrangement and size 30 of the electrodes relatively to the size of the dielectric sheets being such that a portion of each electrode projects in one direction or the other according to its polarity, beyond the corresponding edges of the adjacent dielectric sheets, and such projecting portions 35 have passed therethrough rods in electrical connection therewith which serves to lead thereto or therefrom electric current of appropriate polarity, while the air is caused to 40 pass over all the electrodes in parallel.

It is to be observed that the efficiency (i. e., yield per kilowatt) of an ozone generator, more especially in cases where a highly concentrated product is required, is 45 dependent upon the degree of intimacy of contact between the electrodes and the air which is passed thereover during the ozonizing process. But, the closer the intimacy of contact, the greater is the necessity for 50 passing the air as rapidly as possible over the electrodes so as to obviate an excessive rise of temperature, with consequent disintegration of the ozone produced; and the present invention has for its object to pro-

vide an improved ozone generator of the kind just referred to, so constructed as to permit of a greater production of ozone, relatively to the power consumed or the quantity of air passed through the apparatus, being obtained than with constructions hitherto in use.

A further object of the present invention is to insure that the air in its passage through the apparatus will always follow a path of the same length no matter over which electrode it may pass.

According to the present invention each electrode is of substantially right-angled trapezoidal shape, and the rods which serve to lead to or from the electrodes electric current of appropriate polarity pass through the projecting substantially triangular portions of the electrodes and serve also to clamp together the assemblage of electrodes and dielectric sheets.

Referring to the accompanying drawings, Figure 1 is a face view of one form of electrode. Fig. 2 is a sectional plan on the line 2-2 of Fig. 4 of one form of apparatus constructed in accordance with this invention showing a different form of electrode. Fig. 3 is a section of the assemblage of electrodes with their interposed dielectric sheets, taken as on line 3-3 of Fig. 2, and Fig. 4 is a vertical section taken on the line 4-4 of Fig. 2. Fig. 5 is a sectional view showing a modified arrangement.

Fig. 1 shows an electrode of right-angled trapezoidal shape which may conveniently be cut from a sheet of wire gauze (preferably aluminium) without waste, two such electrodes resulting from an oblique cut across a rectangular sheet. It is preferred, however, to avoid the sharp corner at *a* and to stamp out the sheets as shown by the dotted modifications and as shown in Fig. 2.

The several electrodes are disposed in a series of pairs whereof the two sheets *b* and *c* of a pair, constituting electrodes of opposite polarities, are separated by a dielectric sheet *d* (preferably of mica), those *b* of one polarity being oppositely arranged as shown in Figs. 2 and 4, to those *c* of opposite polarity and alternating with one another and with dielectric sheets *d* in parallel planes throughout the series, so that the electrodes overlap one another throughout a rectangu-

lar area. The dielectric sheets *d* are rectangular and are so much larger than the rectangular area throughout which the electrodes *b*, *c* overlap as to leave a margin extending beyond each edge of said area but beyond three edges only of each electrode, so that a portion of each electrode *b*, *c* projects to the one side or the other as at *e*, *f*, respectively, Fig. 2, beyond the corresponding lateral edges of the adjacent dielectric sheets, *d*, *d*. These sheets are spaced apart from one another by distance pieces *g* extending across the full width of the dielectric sheets *d* and consisting of strips of glass, mica, or other suitable insulating material of a thickness slightly greater than the thickness of the sheet of gauze lying between the correspondingly adjacent dielectric sheets.

20. The entire assemblage of sheets of gauze and dielectric (with the exception of the top and bottom sheets, Fig. 4) is clamped together by rods *h* and *j* which pass through apertures in the projecting portions *e*, *f* of the electrodes *b*, *c* and through washers *k* (preferably of aluminium) which on the one hand maintain the projecting portions of adjacent electrodes *b*, *b*, or *c*, *c* at the correct distance apart, and on the other hand insure good electrical contact between the rod *h* and the electrodes *b* and between the rod *j* and the electrodes *c*. The assemblage is housed within a container whereof the side walls *m*, *m* and the end walls *n*, *n* are constituted by a metal casting and are double so as to provide a watertight jacket *o* through which water may be passed by the inlet and outlet pipe *p*, *q* respectively, and whereof the top *r* and bottom *s* are of insulating material bolted to the metal casting as at *t*, and are provided respectively with an inlet pipe *u* for the air to be ozonized and an outlet pipe *v*. In order to maintain the strips *g* in position and to assist in maintaining the whole assemblage in position, blocks *w* of glass or other insulating material are secured by screws *x* to the inner side walls of the housing, and in order that the respective gauze sheets *b* and *c* may be supplied with electric alternating current the rods *h* and *j* pass through apertures in the top *r* and bottom *s* respectively and are adapted to be connected in any well known manner with electric cables.

55. Within the housing baffle plates *y* and *z* are obliquely disposed as shown in Fig. 4, so that the air passage to and from the assemblage is gradually decreased in cross-sectional area as the distance from the inlet pipe *u* or outlet pipe *v* is increased respectively, thus insuring a uniform distribution of the volume of air passing through the apparatus.

In use, only the rectangular overlapping portions of the electrodes, *b* and *c* are opera-

tive in the ozonizing process, the surplus substantially triangular portions providing an increased cooling surface.

If desired, two assemblages of electrodes may be housed side-by-side within a single container so that the air to be ozonized is caused to pass through the two assemblages in succession, and it will be obvious that any greater number of such assemblages may be similarly housed in a single container in order that the air, being caused to pass through the entire series of assemblages in succession, may be subjected to a cumulative ozonizing process, it being understood that the respective electrodes of either polarity in the several assemblages are suitably interconnected electrically; for instance the electrodes of adjacent assemblages may be so arranged that a single rod *h* will serve to lead current of one polarity to the several electrodes *b* of the assemblage shown in Fig. 4, and of a second assemblage placed on the right thereof, the container being suitably extended, while the rods *j* of the two assemblages are electrically interconnected outside the container.

In Fig. 5 is shown a modification which includes additional means for clamping together the entire assemblage of sheets of gauze and dielectric. In this form of the invention each electrode *b*, *c* is centrally apertured to receive a circular distance piece *l* of glass, mica, or other insulating material serving to space apart the sheets *d* of dielectric material, which sheets, as well as the distance pieces *l* are centrally apertured to admit the passage therethrough of a glass tube *12* in which is disposed a metal rod *13* provided with a nut *14* whereby the several sheets may be clamped together.

What I claim and desire to secure by Letters Patent is;—

1. An ozone generator comprising a plurality of electrodes each consisting of a metallic sheet of substantially right-angled trapezoidal shape, the electrodes of a pair having opposite polarities extending in parallel planes and being separated by a sheet of dielectric material, the arrangement and size of the electrodes relatively to the size of the dielectric sheets being such that a substantially triangular portion of each electrode projects in one direction or the other according to its polarity, beyond the corresponding edges of the dielectric sheets, and rods serving to lead to or from the electrodes electric current of appropriate polarity and passing through the projecting substantially triangular portions of the electrodes, and serving also to clamp together the assemblage of electrodes and dielectric sheets.

2. An ozone generator comprising a plurality of electrodes each consisting of a metallic sheet of substantially right-angled trapezoidal shape, the electrodes of a pair

having opposite polarities extending in parallel planes and being separated by a sheet of dielectric material, the arrangement and size of the electrodes relatively to the size 5 of the dielectric sheets being such that a substantially triangular portion of each electrode projects in one direction or the other according to its polarity, beyond the corresponding edges of the dielectric sheets, 10 rods serving to lead to or from the electrodes electric current of appropriate polarity and passing through the projecting substantially triangular portions of the electrodes, and means for clamping together the assemblage 15 of electrodes and dielectric sheets, said means comprising a nut and a centrally arranged rod disposed in a glass tube passing through apertures in the dielectric sheets and distance pieces of insulating material 20 which are disposed in apertures in the electrodes.

3. An ozone generator comprising a plurality of electrodes each consisting of a metallic sheet of substantially right-angled 25 trapezoidal shape, the electrodes of a pair having opposite polarities extending in parallel planes and being separated by a sheet of dielectric material, the arrangement and size of the electrodes relatively to the size 30 of the dielectric sheets being such that a substantially triangular portion of each electrode projects in one direction or the other according to its polarity, beyond the corresponding edges of the dielectric sheets, 35 rods serving to lead to or from the electrodes electric current of appropriate polarity and passing through the projecting substantially triangular portions of the electrodes, and serving also to clamp together the assemblage 40 of electrodes and dielectric sheets and a container within which said assemblage is housed, said container being provided at its top near one end with an inlet for the air to be ozonized and provided at its bottom near the other end with 45 near the other end with an outlet for the ozonized air.

4. An ozone generator comprising a plurality of electrodes each consisting of a metallic sheet of substantially right-angled 50 trapezoidal shape, the electrodes of a pair having opposite polarities extending in parallel planes and being separated by a sheet of dielectric material, the arrangement and size of the electrodes relatively to the size 55 of the dielectric sheets being such that a substantially triangular portion of each electrode projects in one direction or the other according to its polarity, beyond the corresponding edges of the dielectric sheets, 60 rods serving to lead to or from the electrodes electric current of appropriate polarity and passing through the projecting substantially triangular portions of the electrodes, means for clamping together the assemblage 65 of electrodes and dielectric sheets,

said means comprising a nut and a centrally arranged rod disposed in a glass tube passing through apertures in the dielectric sheets and distance pieces of insulating material which are disposed in apertures in the electrodes, and a container within which said assemblage is housed, said container being provided at its top near one end with an inlet for the air to be ozonized and provided at its bottom near the other end with 70 an outlet for the ozonized air.

5. An ozone generator comprising a plurality of electrodes each consisting of a metallic sheet of substantially right-angled trapezoidal shape, the electrode of a pair 80 having opposite polarities extending in parallel planes and being separated by a sheet of dielectric material, the arrangement and size of the electrodes relatively to the size 85 of the dielectric sheets being such that a substantially triangular portion of each electrode projects in one direction or the other according to its polarity, beyond the corresponding edges of the dielectric sheets, rods serving to lead to or from the electrodes 90 electric current of appropriate polarity and passing through the projecting substantially triangular portions of the electrodes, and serving also to clamp together the assemblage of electrodes and dielectric sheets and a container within which 95 said assemblage is housed, said container being provided at its top near one end with an inlet for the air to be ozonized and provided at its bottom near the other end with 100 an outlet for the ozonized air, said container being also provided with obliquely disposed baffles so that the air passage to and from the assemblage of electrodes is gradually decreased in cross-sectional area as the 105 distance from the inlet pipe or outlet pipe is increased respectively.

6. An ozone generator comprising a plurality of electrodes each consisting of a metallic sheet of substantially right-angled 110 trapezoidal shape, the electrodes of a pair having opposite polarities extending in parallel planes and being separated by a sheet of dielectric material, the arrangement and size of the electrodes relatively to the size 115 of the dielectric sheets being such that a substantially triangular portion of each electrode projects in one direction or the other according to its polarity, beyond the corresponding edges of the dielectric sheets, 120 rods serving to lead to or from the electrodes electric current of appropriate polarity and passing through the projecting substantially triangular portions of the electrodes, means for clamping together the 125 assemblage of electrodes and dielectric sheets, said means comprising a nut and a centrally arranged rod disposed in a glass tube passing through apertures in the dielectric sheets and distance pieces of in- 130

sulating material which are disposed in apertures in the electrodes and a container within which said assemblage is housed, said container being provided at its top 5 near one end with an inlet for the air to be ozonized and provided at its bottom near the other end with an outlet for the ozonized air, said container being also provided with

obliquely-disposed baffles so that the air passage to and from the assemblage of 10 electrodes is gradually decreased in cross-sectional area as the distance from the inlet pipe or outlet pipe is increased respectively.

EDWARD LIONEL JOSEPH.
